(57) **CLAIM**

The ornamental design for a basting brush, as shown and described.

DESCRIPTION

FIG. 1 is a front elevational view of a basting brush showing my new design;

FIG. 2 is a side elevational view thereof;

FIG. 3 is a bottom view thereof; and,

FIG. 4 is a top view thereof.

The rear elevation is identical to the front elevation, the side not illustrated is identical to the side illustration and the broken line showings form no part of the claimed design.
